UNITED STATES PATENT OFFICE.

JOSEPH MACK, OF NEW YORK, N. Y., ASSIGNOR TO ELIAS REISS AND COMPANY, OF NEW YORK, N. Y., A CORPORATION OF NEW YORK.

DESIGN FOR A TEXTILE FABRIC.

Application filed December 5, 1927. Serial No. 24,381. Term of patent 3½ years.

To all whom it may concern:

Be it known that I, JOSEPH MACK, a citizen of Poland, residing at New York, county of New York and State of New York, have invented a new, original, and ornamental Design for a Textile Fabric, of which the following is a specification, reference being had to the accompanying drawing, forming a part thereof.

The new design is disclosed in the accompanying drawing, wherein

Fig. 2 is an enlarged detailed view showing a fragment of the floral decoration of the narrow stripes forming a portion of the design.

I claim:

The ornamental design for a textile fabric as shown and described.

JOSEPH MACK. [L. S.]
